UNITED STATES PATENT OFFICE.

EDWARD WILSON, OF ST. LOUIS, MISSOURI, ASSIGNEE TO WILSON ENGINEERING COMPANY, OF ST. LOUIS, MISSOURI, A CORPORATION OF MISSOURI.

COMPRESSOR.

Application filed March 8, 1921. Serial No. 449,425.

To all whom it may concern:

Be it known that I, EDWARD WILSON, a citizen of the United States, residing at St. Louis, Missouri, have invented a new and useful Compressor, of which the following is a specification.

This invention relates to compressors.

An object of the invention is to provide a compressor of novel and improved construction and mode of operation and in which the compressor mechanism operated by a motor or the like comprises novel and efficient equipment for effecting the compression.

Another object of the invention is to provide a compressor with a valve which is automatic in its operation to control the circulation of the mercury, or the like, which is employed as the agent for effecting compression within a compression chamber.

Another object of the invention is to provide an improved mercury compressor with novel means for causing circulation of the mercury for effecting compression within a compression chamber.

Another object of the invention is to provide an improved mercury compressor with novel equipment for insuring efficient operation and functioning of all of the mechanism, and possessing the characteristic that the parts cannot become dislocated or displaced, but are positively retained in proper adjustment in such manner that they offer a minimum of resistance to the operation of the mechanism.

Another object of the invention is to provide an improved mercury compressor including a mercury chamber and a compression chamber, in combination with novel mechanism for effecting circulation of the mercury into the compression chamber to effect compression therein and for discharging the mercury from the compression chamber after it has performed its function, the construction and operation being such that the mercury is maintained in continuous circulation when the compressor is operating, so that the compression is also continuous.

Various other objects and advantages of my improved compressor will be apparent from the following description in which reference is made to the drawings showing

one embodiment of the invention, and in which—

Fig. 1 is a sectional view of the compressor.

Fig. 2 is a sectional view of the rotor showing other features of the invention and may be considered as taken approximately at right angles to the line on which Fig. 1 is taken.

Fig. 2^a is a plan view of a part of the rotor employed to effect circulation of the mercury.

Fig. 3 is a sectional view of the condenser.

Fig. 4 is a side elevation of the condenser.

In the particular embodiment of the invention shown the stator comprises a number of detachable parts constituting a casting and support for the operative mechanism and forming a chamber or receptacle for the mercury which is employed to effect compression within a compression chamber.

The part 1 of the stator constitutes the receptacle for the mercury and is provided with an upper end wall 2 which supports the part 3 on which the motor 4 is mounted.

The upper wall 2 of the stator is formed with a lubricant receptacle 5 to which lubricant may be delivered through a vent 6 equipped with a removable plug.

The upper end wall 2 of the stator supports a member 7 which carries an anti-friction bearing 8 while the upper wall 2 carries another anti-friction bearing 9. A shaft 10 is supported for rotation in the bearings 8 and 9.

Between said bearings 8 and 9 the shaft 10 operates within a packing bearing including a sleeve 11 having circumferential flanges operating within grooves in a housing 12.

Packing material 13 is supported within the inner end of the sleeve 11 and is compressed therein by a member 14.

A spring 15 is interposed between the member 14 and the upper end of the hub of the rotor which is attached to the inner end of the shaft 10, and acts to press the parts of the packing bearing close together to maintain a perfect seal and prevent the passage of air between said parts.

A wick 16 extending into the lubricant in the lubricant receptacle 5 serves to conduct the lubricant to the bearing for the shaft 10.

A rotor which operates within the stator housing is driven by the shaft 10. The ro-

tor comprises means for effecting circulation of the mercury into a compression chamber in the rotor to cause compression in said chamber, and then returning the mercury 5 from the compression chamber to the stator receptacle. This operation is continuous and the mercury is successively passed through the rotor to maintain continuity of compression. The rotor shown comprises 10 an upper part 17 having an axial hub journaled in the bearing 9 and secured to the shaft 10; and a lower part 18 attached to the part 17. A compression chamber 19 is formed between the parts 17 and 18 and it 15 is by the circulation of the mercury through the chamber 19 that compression is obtained.

The upper part 17 of the rotor has a central chamber 20 across which the part 21 extends, the same being integral or otherwise made rigid with the upper part 17 of the rotor. In the operation of the rotor the mercury is taken up into the chamber 20 between the part 21 and the walls of the chamber 20 in which said part 21 is supported. The mercury may be raised and delivered into the chamber 20 by any appropriate means. As shown the means for raising and delivering the mercury from the stator to the 30 chamber 20 comprises a number of impeller vanes 22 made rigid or integral with a part 23 which is in connection with the rotor. The impeller vanes are arranged obliquely, having their lower ends in advance or in 35 front of their upper ends, considering the direction of rotation of the rotor. This will be clearly understood by reference to Fig. 2^a in which the impeller vanes are shown, it being intended that the rotor revolve in a 40 counter-clockwise direction when the impeller vanes are arranged as there shown. Of course, it is obvious that the direction of rotation of the rotor is wholly immaterial, it being important only that the impeller 45 vanes shall be effective to raise and deliver the mercury into the chamber 20; and if it is desired to rotate the rotor in a clockwise direction the impeller vanes will, of course, be inclined in the other direction 50 from that shown.

The mercury is taken up by the impeller vanes 22 from an annular space into which the mercury rises. The annular space mentioned is that annular space left between the 55 tubular extension 24 of the part 23 and a cylindrical member 25 in connection with the part 21 and extending downwardly within said tubular extension 24. The stator contains mercury to about the depth shown, 60 the lower ends of the impeller vanes being immersed in the mercury so that when the compressor is placed in operation the mercury will be continuously raised by the impeller vanes and delivered into the chamber 65 20. During such operation all of the mer-

cury within the stator will be delivered into the rotor, except that relatively small amount of mercury below the ends of the cylindrical chamber walls 24 and 25, if that amount of mercury be required in the 70 stator. Undesired disturbance of the body of mercury within the stator by the rotation of the rotor is prevented by a baffle 26 secured to a stationary support 27 which is in connection with the stator wall 1. A small 75 annular space is left between the baffle 26 and the adjacent portion of the rotor into and from which the mercury is free to pass.

The part 21 of the rotor is rigid with a hollow shaft 28 which extends through the lower wall of the part 1 and is journaled in an anti-friction bearing 29 supported by said lower wall. A sleeve 30 has its lower end forming an hermetic and impervious joint with the lower wall of the part 1, and extends upwardly within the cylindrical member 25. The upper end of the sleeve 30 is above the level of the mercury in the stator so that it is impossible for the mercury to pass through the opening in the lower wall of the stator part 1, through which the hollow shaft 28 extends.

As before stated the rotor contains a compression chamber 19. It is by forcing the mercury into the compression chamber 19 that compression is obtained. The mercury is delivered into the compression chamber 19 by centrifugal force and the flow of the mercury to the compression chamber is controlled by an improved valve device which operates automatically to open and to close communication from the chamber 20 to the compression chamber 19. The valve device mentioned is clearly shown in Fig. 1 and comprises a valve 31 on the end of an axially movable valve stem 32 extending through the passage 33 forming a communication from the chamber 20 to the compressor chamber 19. There is sufficient space around the stem 32 within the passage 33 to permit the mercury to move through said passage under the impulse of centrifugal force. The opposite end of the valve stem 32 comprises an enlarged weighted part 34, the weight of which exceeds the combined weight of the valve 31 and the small part of the stem 32. The valve stem 32, including the weighted portion 34, extends diametrically across the rotor and is capable of axial movements to and from position to close the valve 31. Since the weighted end 34 of the valve stem is heavier than the valve 31 and the small part of the stem 32 and extends about the axis of the rotor, it is an obvious fact that when the rotor is operating the valve 31 will be held closed, due to centrifugal force, until the greater weight of the weighted end 34 of the valve stem is overcome. The parts are arranged and proportioned properly so that when the chamber 130

ber 20 and the passage 33 become filled with mercury the pressure of the mercury against the valve 31, under the impulse of centrifugal force, will overcome the resistance 5 of the weighted end 34 of the valve. When this occurs the valve 31 is moved radially away from its seat against the end of the passage 33, thus permitting the mercury to move centrifugally through said passage 33 10 and into the compression chamber 19. The outer end of the walls of the passage 33 is within an enclosing part 35, having a discharge opening 36 in the end thereof. The opening 36 is normally in communication 15 with the compression chamber 19, but is closed by the valve 31 when said valve is forced centrifugally from the end of the passage 33 to permit the mercury to pass into the compression chamber. Obviously, 20 as the mercury is forced into the compression chamber there is a compression of air in said chamber. As the compressed air from the compression chamber passes therefrom into the stator, as hereinafter explained, 25 the air within the stator is compressed and, since there are rapidly successive operations of compression of the character described, the air within the compressor becomes greatly compressed.

30 When the desired degree of compression is obtained in the compression chamber 19 as a result of the delivery of the mercury into said chamber under the impulse of centrifugal force as described, the compressed 35 air and the mercury are discharged from said compression chamber 19 into the stator case or housing. As the successive operations of compression are continuous the result is that a high degree of compression is 40 obtained. The discharge of the compressed air and the mercury from the compression chamber 19 is effected through a valve controlled discharge passage. The discharge passage includes an opening 37 (Fig. 2) 45 through one wall of the chamber 19 communicating with an opening 38 into the stator casing or housing. The valve 39 is at the inner end of the opening 37 and is of a yielding structure which normally retains 50 the valve in position to close the opening 37. Moreover, the centrifugal force created by the rotation of the rotor also acts upon the valve 39 to hold the valve closed until 55 the desired degree of compression is obtained within the compression chamber 19. When the desired degree of compression is obtained in said compression chamber 19, the valve 39 is opened by the pressure from 60 within the chamber overcoming the inherent tendency of the valve to remain closed, as well as the centrifugal pressure against the valve. This permits the compressed air and a part of the mercury in the compression chamber 19 to pass through the discharge 65 passage, comprising the opening 37 and the

passage 38. However, since the passage 37-38 leads inwardly from the compression chamber, some part of the mercury will not pass through said passage, but will be discharged from the compression chamber 70 through the opening 36, as described in the next paragraph. The compressed air is thereby delivered or discharged into the stator casing or housing and the mercury returns to the stator casing or housing. The 75 operation of compression as above described is successively performed.

It will be understood that after the mercury is discharged from the passage 33 (Fig. 1) into the compression chamber 19, the 80 valve 31 is restored to position to close the end of the passage 33 and to open the opening 36, but this does not occur until the valve 39 is opened. When the opening 36 is opened by the valve 31 moving therefrom to close 85 the passage 33, as described, the remainder of the mercury in the compression chamber 19 is caused, under the impulse of centrifugal force, to pass from the compression chamber 19 through the opening 36 into the 90 stator casing. As a result of the operation described, the pressure within the compression chamber 19 becomes reduced below atmospheric pressure so that it is possible for fresh air to enter the compression chamber 95 preparatory for the next compression. The fresh air is admitted to the compression chamber 19 through a valve controlled passage 40 (Fig. 2) communicating with the hollow shaft 28. The lower end of the shaft 28 is within a chamber 41. The shaft 28 within the chamber 41 is protected by a mercury seal comprising a bell 42, the rim of which is immersed in mercury contained 100 in an annular receptacle 43 formed between the wall of the chamber 41 and a cylindrical flange 44 rising from the bottom wall of said chamber 41. There is an opening 45 through the bottom wall of the chamber 41 which is closed by a cup 46 movably supported 105 within the cylindrical flange 44. The cup 46 receives and traps any quantity of mercury that may pass through the passage 40 and the shaft 28, but permits air to be drawn by suction through the shaft 28 for delivery 110 into the compression chamber 19. The suction is created as a result of the discharge of the compressed air and the mercury from the chamber 19 and, further, as a result of the centrifugal force causing a reduction of 115 the pressure in the chamber 19 below the pressure in the stator casing or housing. 120

As shown (Fig. 2) the passage 40 is controlled by a suction valve comprising a valve member 47 and a spring 48 acting to hold 125 the valve closed, but permitting the valve to open under the pressure of the air drawn through the shaft 28 by suction.

The compressed air from the stator casing or housing passes through a passage 49 130

(Fig. 1) to a condenser. The condenser may be of any desired construction and arrangement. A preferred form is shown. The condenser shown comprises a member containing numerous radial chambers 50 (Figs. 3 and 4) in communication with the passage 49 and arranged to receive the compressed air from said passage. The walls of the radial chambers 50 are immersed in water in a container 51 under the influence of which condensation is effected. The condenser is in communication with the chamber 41 through the space or clearance 52 around the shaft 28 in the bottom of the condenser, and the chamber 41 is in communication with the usual coils (not shown).

From the foregoing it will be seen that my invention is characterized by numerous advantageous features which are cooperatively related so that the condenser will perform its functions in a highly efficient manner. Many of the unessential features shown have not been described in detail, and it is apparent that as to such features and many others the compressor may be varied in its construction and arrangement without departing from the principle and nature of the invention. I have not intended to restrict myself to unessential features, nor otherwise, except as set forth in the appended claims.

What I claim and desire to secure by Letters Patent, is:—

1. A compressor, comprising a stator casing arranged to contain a quantity of mercury, a rotor journaled for rotation within the stator, a compression chamber in the rotor, a receiving chamber in the rotor, means for conveying the mercury from the stator to the receiving chamber in the rotor, a passage from the receiving chamber to the compression chamber in the rotor, and a valve controlling said passage and preventing the mercury from passing from the receiving chamber to the compression chamber until a predetermined pressure of the mercury against said valve exists.

2. A compressor, comprising a stator casing arranged to contain a quantity of mercury, a rotor journaled for rotation within the stator, a compression chamber in the rotor, a receiving chamber in the rotor, means for conveying the mercury from the stator to the receiving chamber in the rotor, a passage from the receiving chamber to the compression chamber in the rotor, a valve controlling said passage and preventing the mercury from passing from the receiving chamber to the compression chamber until a predetermined pressure of the mercury against said valve exists, and a valve controlling the discharge of pressure from the compression chamber into the stator casing.

3. A compressor of the character described, comprising a stator casing arranged to contain a quantity of mercury, a rotor

supported for rotation in the stator casing, a compression chamber in the rotor, a passage through the rotor to the compression chamber, a valve supported by the rotor and arranged to be held in closed position by centrifugal force when the rotor is rotating until the pressure against the valve exceeds the centrifugal force, and means for forcing the mercury from the stator casing through said passage to open said valve and into the compression chamber to effect compression therein.

4. A compressor of the character described, comprising a stator casing arranged to contain a quantity of mercury, a rotor supported for rotation in the stator casing, a compression chamber in the rotor, a passage through the rotor to the compression chamber, a valve supported by the rotor and arranged to be held in closed position by centrifugal force when the rotor is rotating until the pressure against the valve exceeds the centrifugal force, means for forcing the mercury from the stator casing through said passage to open said valve and into the compression chamber to effect compression therein, and a valve controlling discharge of pressure from the compression chamber into the stator casing.

5. A compressor of the character described, comprising a stator casing arranged to contain a quantity of mercury, a rotor supported for rotation in the stator casing, a compression chamber in the rotor, a passage through the rotor to the compression chamber, a valve supported by the rotor and arranged to be held in closed position by centrifugal force when the rotor is rotating until the pressure against the valve exceeds the centrifugal force, means for forcing the mercury from the stator casing through said passage to open said valve and into the compression chamber to effect compression therein, and means for admitting air into the compression chamber for compression.

6. A compressor of the character described, comprising a stator casing arranged to contain a quantity of mercury, a rotor supported for rotation in the stator casing, a compression chamber in the rotor, a passage through the rotor to the compression chamber, a valve supported by the rotor and arranged to be held in closed position by centrifugal force when the rotor is rotating until the pressure against the valve exceeds the centrifugal force, means for forcing the mercury from the stator casing through said passage to open said valve and into the compression chamber to effect compression therein, a valve controlling discharge of pressure from the compression chamber into the stator casing, and means for admitting air in the compression chamber successively for compression by successive operations as aforesaid.

7. A compressor of the character described, comprising a stator casing, a rotor supported for rotation in the stator casing, a compression chamber in the rotor, a passage through the rotor for conducting mercury from the stator casing to the compression chamber in the rotor, means operating with the rotor for causing the mercury to pass through said passage, and a valve held 10 in one position by centrifugal force and movable to another position under the pressure of the mercury passing to the compression chamber to admit the mercury into said chamber.
8. A compressor, comprising a stator casing arranged to contain mercury, a rotor supported for rotation in the stator casing, a compression chamber in the rotor, a passage through the rotor for conducting mercury from the stator into said compression chamber, a valve controlling said passage and arranged to be retained in closed position by centrifugal force when the rotor is rotated, and means operating with the rotor 20 for causing the mercury to pass into said passage to open said valve and to pass into the compression chamber.
9. A compressor, comprising a stator casing arranged to contain mercury, a rotor supported for rotation in the stator casing, a compression chamber in the rotor, a passage through the rotor for conducting mercury from the stator into said compression chamber, a valve controlling said passage and arranged to be retained in closed position by centrifugal force when the rotor is rotated, means operating with the rotor for causing the mercury to pass into said passage to open said valve and to pass into the compression chamber, and means for controlling the discharge of the compressed air from said compression chamber.
10. A compressor, comprising a stator casing arranged to contain mercury, a rotor supported for rotation in the stator casing, a compression chamber in the rotor, a passage through the rotor for conducting mercury from the stator into said compression chamber, a valve controlling said passage and arranged to be retained in closed position by centrifugal force when the rotor is rotated, means operating with the rotor for causing the mercury to pass into said passage to open said valve and to pass into the compression chamber, means for controlling the discharge of the compressed air from said compression chamber, and means for delivering a fresh supply of air into the compression chamber.
11. A compressor, comprising a stator casing arranged to contain mercury, a rotor supported for rotation in the stator casing, a compression chamber in the rotor, a passage through the rotor opening into the compression chamber, a valve stem extending 60 diametrically across the rotor within said passage, a valve on one end of said valve stem for closing said passage, and a weight on the opposite end of said valve stem effected by said centrifugal force to hold said valve closed.
12. A compressor, comprising a stator casing arranged to contain mercury, anti-friction bearings supported by the walls of said stator casing, a rotor supported by said bearings for rotation in said casing, an annular compression chamber in said rotor, a radial passage from the center of the rotor communicating with said compression chamber, a valve controlling said passage, and means operated by the rotor for delivering mercury into said passage to press against and open said valve and enter the compression chamber to effect compression therein under the impulse of centrifugal force.
13. A compressor, comprising a stator casing arranged to contain mercury, anti-friction bearings supported by the walls of said stator casing, a rotor supported by said bearings for rotation in said casing, an annular compression chamber in said rotor, a radial passage from the center of the rotor communicating with said compression chamber, a valve controlling said passage, means operated by the rotor for delivering mercury into said passage to press against and open said valve and enter the compression chamber to effect compression therein under the impulse of centrifugal force, and a valve controlled passage for permitting compression to pass from said compression chamber into the stator casing.
14. A compressor, comprising a stator casing arranged to contain mercury, anti-friction bearings supported by the walls of said stator casing, a rotor supported by said bearings for rotation in said casing, an annular compression chamber in said rotor, a radial passage from the center of the rotor communicating with said compression chamber, a valve controlling said passage, means operated by the rotor for delivering mercury into said passage to press against and open said valve and enter the compression chamber to effect compression therein under the impulse of centrifugal force, a valve controlled passage for permitting compression to pass from said compression chamber into the stator casing, and a passage for conducting fresh air into the compression chamber.
15. A compressor, comprising a stator casing, a rotor journaled for rotation in said casing, a central chamber in said rotor, an annular compression chamber in said rotor, a radial passage from the central chamber communicating with the compression chamber, an annular passage from the central chamber to the bottom of the stator casing, and impeller vanes supported by the rotor for 120 130

causing mercury to flow through said annular passage into said central chamber.

16. A compressor, comprising a stator casing, a rotor journaled for rotation in said casing, a central chamber in said rotor, an annular compression chamber in said rotor, a radial passage from the central chamber communicating with the compression chamber, an annular passage from the central chamber to the bottom of the stator casing, impeller vanes supported by the rotor for causing mercury to flow through said annular passage into said central chamber, and a valve in the passage from the central chamber to the compression chamber controlling the centrifugal movement of the mercury to the compression chamber.

17. A compressor, comprising a stator casing arranged to contain mercury, a rotor supported for rotation in the stator casing, a compression chamber in the rotor between the axis of the rotor and its outer circumference, a passage through the rotor extending outwardly from near the axis of the rotor to said compression chamber, means operating with the rotor for causing the mercury to move into said passage, a valve controlling said passage and arranged to open under pressure of the mercury actuated by centrifugal force to permit the mercury to pass into the compression chamber to effect compression therein, and automatic means for closing said valve after a quantity of the mercury has passed said valve into the compression chamber.

18. A compressor, comprising a stator casing arranged to contain mercury, a rotor supported for rotation in the stator casing, a compression chamber in the rotor between the axis of the rotor and its outer circumference, a passage through the rotor extending outwardly from near the axis of the rotor to said compression chamber, means operating with the rotor for causing the mercury to move into said passage, a valve controlling said passage and arranged to open under pressure of the mercury actuated by centrifugal force to permit the mercury to pass into the compression chamber to effect compression therein, and means operated by the centrifugal force during rotation of the rotor for closing said valve after a quantity of mercury has passed said valve and has effected compression in said compression chamber.

19. A compressor, comprising a stator casing arranged to contain mercury, a rotor supported for rotation in the stator casing, a compression chamber in the rotor between the axis of the rotor and its outer circumference, a passage through the rotor extending outwardly from near the axis of the rotor to said compression chamber, means operating with the rotor for causing the mercury to move into said passage, a

valve controlling said passage and arranged to open under pressure of the mercury actuated by centrifugal force to permit the mercury to pass into the compression chamber to effect compression therein, automatic means for closing said valve after a quantity of the mercury has passed said valve into the compression chamber, and a valve controlling discharge of pressure from said compression chamber into the stator and arranged to open under the pressure of the compression in said chamber and to close when compression has passed from said compression chamber into the stator.

20. A compressor, comprising a stator casing arranged to contain mercury, a rotor supported for rotation in the stator casing, a compression chamber in the rotor between the axis of the rotor and the circumference thereof, an outlet passage from the compression chamber, a passage from near the axis of the rotor opening into the compression chamber, a valve for opening and closing said two passages, means for holding said valve in position to close said second passage when less than a predetermined amount of mercury is in said second passage, and means operating with the rotor to cause mercury to pass into said second passage and under the impulse of centrifugal force to move said valve from position to open said second passage and to close said first-named passage.

21. A compressor, comprising a stator casing arranged to contain mercury, a rotor supported for rotation in said casing, a compression chamber in the rotor between the axis of the rotor and the circumference thereof, a passage from the central part of the rotor to the compression chamber, a valve controlled by centrifugal force during rotation of the rotor to close said passage, and means for delivering the mercury from the stator casing into said passage whereby the mercury under the impulse of centrifugal force will open said valve and pass into the compression chamber and effect compression in said chamber.

22. A compressor, comprising a stator casing arranged to contain mercury, a rotor supported for rotation in said casing, a compression chamber in the rotor between the axis of the rotor and the circumference thereof, a passage from the central part of the rotor to the compression chamber, a valve controlled by centrifugal force during rotation of the rotor to close said passage, means for delivering the mercury from the stator casing into said passage whereby the mercury under the impulse of centrifugal force will open said valve and pass into the compression chamber and effect compression in said chamber, and an outlet passage from the compression chamber which is closed by said valve when said valve is moved by

the mercury as aforesaid and which is open when said valve is in position to close said first-named passage.

23. A compressor, comprising a stator 5 casing arranged to contain mercury, a rotor supported for rotation in said casing, a compression chamber in said rotor, a series of impeller vanes supported by the rotor for imparting initial movement of the mercury 10 toward said compression chamber, a valve arranged to open by the pressure of the mercury passing to the compression chamber, and means actuated by centrifugal force to close said valve.

15 24. A compressor, comprising a stator casing arranged to contain mercury, a rotor supported for rotation in said casing, a compression chamber in said rotor, a series of impeller vanes supported by the rotor for 20 imparting initial movement of the mercury toward said compression chamber, and a valve controlling the movement of the mercury into the compression chamber.

25 25. A compressor, comprising a stator casing arranged to contain mercury, a rotor supported for rotation in said casing, a compression chamber in said rotor, a passage for conducting the mercury from the stator casing into said compression chamber, a 30 valve controlling the passage of mercury to the compression chamber and arranged to open under pressure of the mercury in said passage, and a series of impeller vanes supported by the rotor and having their lower ends immersed in the mercury in the stator casing and arranged to impart initial movement of the mercury from the stator casing through said passage to the compression chamber.

40 26. A compressor, comprising a stator casing arranged to contain mercury, a rotor supported for rotation in said casing, a compression chamber in said rotor, a passage for conducting the mercury from the stator casing into said compression chamber, a 45 series of impeller vanes supported by the rotor and having their lower ends immersed in the mercury in the stator casing and arranged to impart initial movement of the mercury from the stator casing through said passage to the compression chamber, and a valve in said passage preventing flow of the mercury into the compression chamber until a predetermined quantity of the mercury is 50 in said passage arranged to open under the pressure of the mercury to permit the mercury to pass into said passage.

55 27. A compressor, comprising a stator casing arranged to contain mercury, a rotor supported for rotation in said casing, a compression chamber in said rotor, a passage for conducting the mercury from the stator casing into said compression chamber, a series of impeller vanes supported by the 60 rotor and having their lower ends immersed

in the mercury in the stator casing and arranged to impart initial movement of the mercury from the stator casing through said passage to the compressor chamber, a valve in said passage preventing flow of the mercury into the compression chamber until a predetermined quantity of the mercury is in said passage arranged to open under the pressure of the mercury to permit the mercury to pass into said passage, and means 70 for closing said valve after the mercury has passed into the compression chamber.

75 28. A compressor, comprising a stator casing arranged to contain mercury, a rotor supported for rotation in said casing, a compression chamber in said rotor, a passage for conducting the mercury from the stator casing into said compression chamber, a valve controlling the passage of mercury to the compression chamber and arranged to open under pressure of the mercury in said passage, a series of impeller vanes supported by the rotor and having their lower ends immersed in the mercury in the stator casing and arranged to impart initial movement of the mercury from the stator casing through said passage to the compression chamber, and a passage controlling the discharge of the compression and the mercury from said compression chamber into the stator casing.

80 29. A compressor, comprising a stator casing arranged to contain mercury, a rotor supported for rotation in said casing, a compression chamber in said rotor, a passage for conducting the mercury from the stator casing into said compression chamber, a series of impeller vanes supported by the rotor and having their lower ends immersed in the mercury in the stator casing and arranged to impart initial movement of the mercury from the stator casing through said passage to the compression chamber, a valve in said passage preventing flow of the mercury into the compression chamber until a predetermined quantity of the mercury is in said passage arranged to open under the pressure of the mercury to permit the mercury to pass into said passage, and a passage for the discharge of the compression and the mercury from said compression chamber into the stator casing.

85 30. A compressor, comprising a stator casing arranged to contain mercury, a rotor supported for rotation in said casing, a compression chamber in said rotor, a passage for conducting the mercury from the stator casing into said compression chamber, a series of impeller vanes supported by the rotor and having their lower ends immersed in the mercury in the stator casing and arranged to impart initial movement of the mercury from the stator casing through said passage to the compression chamber, a valve in said passage preventing flow of the mercury into the compression chamber until a predeter- 90 95 100 105 110 115 120 125 130

- mined quantity of the mercury is in said passage arranged to open under the pressure of the mercury to permit the mercury to pass into said passage, means for closing 5 said valve after the mercury has passed into the compression chamber, and a passage for the discharge of the compression and the mercury from said compression chamber into the stator casing.
- 10 31. A compressor, comprising a stator casing arranged to contain mercury, a rotor supported for rotation in said casing, a compression chamber in the rotor, a passage for conducting the mercury from the stator casing into said compression chamber to effect compression in said chamber, means supported by the rotor for imparting initial movement of the mercury from the stator casing through said passage to said compression chamber, a valve controlling said passage arranged to yield to the pressure of the mercury under the impulse of centrifugal force to open said passage to permit the mercury to pass into said compression chamber to effect compression therein, means for discharging compression from the compression chamber into the stator casing, a condenser, and a passage 20 communicating with the condenser from the stator casing.
- 25 32. A compressor, comprising a stator casing arranged to contain mercury, a rotor supported for rotation in the stator casing, a receiving chamber in the rotor communicating with the compression chamber, a valve closing communication from the receiving chamber to the compression chamber, means acting under centrifugal force to hold said valve closed and leaving said 30 valve free to be moved to open position by the pressure of the mercury under centrifugal force, impeller vanes supported by the rotor for delivering mercury from the stator casing into the receiving chamber, and means controlling the discharge of the mercury and the compression from the compression chamber.
- 35 33. A compressor, comprising a stator casing arranged to contain mercury, a rotor supported for rotation in the stator casing, a receiving chamber in the rotor communicating with the compression chamber, a valve closing communication from the receiving chamber to the compression chamber, means acting under centrifugal force to hold said valve closed and leaving said 40 valve free to be moved to open position by the pressure of the mercury under centrifugal force, impeller vanes supported by the rotor for delivering mercury from the stator casing into the receiving chamber, and means controlling the discharge of the mercury and the compression from the compression chamber.
- 45 34. A compressor, comprising a stator casing arranged to contain mercury, anti-friction bearings supported by the stator casing, a rotor within the stator casing journaled for rotation in said bearings, a compression chamber in the rotor, means for delivering mercury under the impulse of centrifugal force from the stator casing into said compression chamber to effect compression in said chamber, a valve controlling discharge of the mercury and the compression from the compression chamber into the stator, a device actuated by centrifugal force for opening said valve to permit discharge of the mercury and the compression from the compression chamber into the stator, and an air supply passage through the axis of the rotor for delivering air into said compression chamber.
- 50 35. A compressor, comprising a stator casing arranged to contain mercury, anti-friction bearings supported by the stator casing, a rotor within the stator casing journaled for rotation in said bearings, a compression chamber in the rotor, means for delivering mercury under the impulse of centrifugal force from the stator casing into said compression chamber to effect compression in said chamber, a valve controlling discharge of the mercury and the compression from the compression chamber into the stator, a device actuated by centrifugal force for opening said valve to permit discharge of the mercury and the compression from the compression chamber into the stator, an air supply passage through the axis of the rotor for delivering air into said compression chamber, and a valve supported by the rotor controlling said passage.
- 55 36. A compressor, comprising a rotor, a compression chamber in the rotor, a passage for admitting mercury into the compression chamber for effecting compression therein, a valve controlling said passage, and a centrifugal device holding said valve closed and arranged to yield to the pressure of the mercury at the proper time to permit the mercury to pass into the compression chamber.
- 60 37. A compressor, comprising a rotor, a compression chamber in the rotor, a passage for admitting mercury into the compression chamber for effecting compression therein, a valve controlling said passage, a centrifugal device holding said valve closed and arranged to yield to the pressure of the mercury at the proper time to permit the mercury to pass into the compression chamber, a discharge passage from the compression chamber, and a valve controlling said discharge passage and arranged to yield when the desired compression has been ob-

the compression chamber to said condenser.

34. A compressor, comprising a stator casing arranged to contain mercury, anti-friction bearings supported by the stator casing, a rotor within the stator casing journaled for rotation in said bearings, a compression chamber in the rotor, means for delivering mercury under the impulse of centrifugal force from the stator casing into said compression chamber to effect compression in said chamber, a valve controlling discharge of the mercury and the compression from the compression chamber into the stator, a device actuated by centrifugal force for opening said valve to permit discharge of the mercury and the compression from the compression chamber into the stator, and an air supply passage through the axis of the rotor for delivering air into said compression chamber.

35. A compressor, comprising a stator casing arranged to contain mercury, anti-friction bearings supported by the stator casing, a rotor within the stator casing journaled for rotation in said bearings, a compression chamber in the rotor, means for delivering mercury under the impulse of centrifugal force from the stator casing into said compression chamber to effect compression in said chamber, a valve controlling discharge of the mercury and the compression from the compression chamber into the stator, a device actuated by centrifugal force for opening said valve to permit discharge of the mercury and the compression from the compression chamber into the stator, an air supply passage through the axis of the rotor for delivering air into said compression chamber, and a valve supported by the rotor controlling said passage.

36. A compressor, comprising a rotor, a compression chamber in the rotor, a passage for admitting mercury into the compression chamber for effecting compression therein, a valve controlling said passage, and a centrifugal device holding said valve closed and arranged to yield to the pressure of the mercury at the proper time to permit the mercury to pass into the compression chamber.

37. A compressor, comprising a rotor, a compression chamber in the rotor, a passage for admitting mercury into the compression chamber for effecting compression therein, a valve controlling said passage, a centrifugal device holding said valve closed and arranged to yield to the pressure of the mercury at the proper time to permit the mercury to pass into the compression chamber, a discharge passage from the compression chamber, and a valve controlling said discharge passage and arranged to yield when the desired compression has been ob-

tained in said chamber to permit the compression and the mercury to pass from said chamber.

38. A compressor, comprising a rotor, a compression chamber in the rotor, a passage for admitting mercury into the compression chamber for effecting compression therein, a valve controlling said passage, a centrifugal device holding said valve closed 10 and arranged to yield to the pressure of the mercury at the proper time to permit the mercury to pass into the compression chamber, a discharge passage from the compression chamber, a valve controlling said 15 discharge passage and arranged to yield when the desired compression has been obtained in said chamber to permit the compression and the mercury to pass from said chamber, a condenser, and a passage for 20 conveying to the condenser the compression that is discharged from the compression chamber.

39. A compressor, comprising a stator casing arranged to contain mercury, a rotor journaled for rotation in the stator casing, a compression chamber in the rotor, a receiving chamber in the rotor communicating with the compression chamber, a valve controlling discharge of the mercury and the 30 compression from the compression chamber into the stator, a device actuated by centrifugal force for opening said valve to permit discharge of the mercury and the compression from the compression chamber into 35 the stator, a passage for admitting mercury to the receiving chamber from the stator casing, and a series of inclined impeller vanes in said passage for delivering mercury into the receiving chamber as an incident to the 40 rotation of the rotor.

40. A compressor, comprising a stator casing arranged to contain mercury, a rotor journaled for rotation in the stator casing, a compression chamber in the rotor, a receiving chamber in the rotor communicating with the compression chamber, a passage for admitting mercury to the receiving chamber from the stator casing, a series of inclined impeller vanes in said passage for 45 delivering mercury into the receiving chamber as an incident to the rotation of the rotor, and a valve controlling the discharge of the mercury from the receiving chamber into the compression chamber.

41. A compressor, comprising a stator casing arranged to contain mercury, a rotor journaled for rotation in the stator casing, a compression chamber in the rotor, a receiving chamber in the rotor communicating 50 with the compression chamber, a passage for admitting mercury to the receiving chamber from the stator casing, a series of inclined impeller vanes in said passage for delivering mercury into the receiving chamber as an 55 incident to the rotation of the rotor, a valve

controlling the discharge of the mercury from the receiving chamber into the compression chamber, and a centrifugal device holding said valve closed until the desired quantity of mercury has accumulated in the receiving chamber and permitting the valve to be opened by the pressure of the mercury against said valve when the desired quantity of mercury has been received in the receiving chamber. 75

42. A compressor, comprising a stator casing arranged to contain mercury, a rotor journaled for rotation in the stator casing, a compression chamber in the rotor, a receiving chamber in the rotor communicating with the compression chamber, a passage for admitting mercury to the receiving chamber from the stator casing, a series of inclined impeller vanes in said passage for delivering mercury into the receiving chamber as an incident to the rotation of the rotor, a valve controlling the discharge of the mercury from the receiving chamber into the compression chamber, a centrifugal device holding said valve closed until the desired quantity of mercury has accumulated in the receiving chamber and permitting the valve to be opened by the pressure of the mercury against said valve when the desired quantity of mercury has been received in the receiving chamber, and an outlet from the compression chamber arranged to be closed by said valve when the valve is moved by the mercury as aforesaid. 90

43. A compressor, comprising a stator casing arranged to contain mercury, a rotor journaled for rotation in said casing, a compression chamber in the rotor, a receiving chamber in the rotor communicating with the compression chamber, an outlet from the compression chamber, a valve controlling communication from the receiving chamber to the compression chamber and controlling the outlet from the compression chamber, a centrifugal device for holding said valve in position to close communication from the receiving chamber to the compression chamber and to leave said outlet open, and means for causing the mercury to enter the receiving chamber and to press against said valve effectively to open communication to the compression chamber and to cause said valve to close said outlet. 105 110

44. A compressor, comprising a stator casing arranged to contain mercury, a rotor journaled for rotation in the stator casing, a receiving chamber in the rotor, an outlet from the compression chamber, a passage from the receiving chamber to the compression chamber, a valve movable from position to close said passage to position to close said outlet and vice versa, means for delivering mercury into said receiving chamber, and a centrifugal device for holding said valve in position to close said passage 120 125 130

and leaving the valve free to be moved by the pressure of the mercury from the receiving chamber to position to open said passage and to close said outlet to permit the mercury to pass through said passage into the compression chamber to effect compression in said chamber.

45. A compressor, comprising a stator casing arranged to contain mercury, a rotor journaled for rotation in the stator casing, a receiving chamber in the rotor, an outlet from the compression chamber, a passage from the receiving chamber to the compression chamber, a valve movable from position to close said passage to position to close said outlet and vice versa, means for delivering mercury into said receiving chamber, a centrifugal device for holding said valve in position to close said passage and leaving the valve free to be moved by the pressure of the mercury from the receiving chamber to position to open said passage and to close said outlet to permit the mercury to pass through said passage into the compression chamber to effect compression in said chamber, means for discharging the compression from the compression chamber, a condenser arranged to receive the compression, and means for delivering air into the compression chamber after each compression has been completed.
46. A compressor, comprising a stator casing arranged to contain mercury, a rotor journaled for rotation in the stator casing, a receiving chamber in the rotor, an outlet from the compression chamber, a passage from the receiving chamber to the compression chamber, a valve movable from position to close said passage to position to close said outlet and vice versa, means for delivering mercury into said receiving chamber, a centrifugal device for holding said valve in position to close said passage and leaving the valve free to be moved by the pressure of the mercury from the receiving chamber to position to open said passage and to close said outlet to permit the mercury to pass through said passage into the compression chamber to effect compression in said chamber, means for discharging the compression from the compression chamber, a condenser arranged to receive the compression, and means for delivering air into the compression chamber after each compression has been completed.

47. A compressor, comprising a rotor, a compression chamber in the rotor, a receiving chamber in the rotor, means for delivering mercury into the receiving chamber, a passage from the receiving chamber to the compression chamber, a valve controlling said passage, and a centrifugal device controlling said valve.

EDWARD WILSON.
